UNITED STATES PATENT OFFICE.

EGBERT N. BAGLEY, OF PITTSBURG, KANSAS.

SHIPPING-CASE.

No. 926,587

Specification of Letters Patent. Patented June 29, 1909.

Application filed March 17, 1908. Serial No. 421,605.

To all whom it may concern:

Be it known that I, EGBERT N. BAGLEY, a citizen of the United States, residing at Pittsburg, in the county of Crawford and State of Kansas, have invented new and useful Improvements in Shipping-Cases, of which the following is a specification.

This invention relates to improvements in shipping boxes or cases, the objects of the invention being to provide, first, a simple, strong and durable construction of case formed of wood and sheet-metal; second, a box or case of this character in which the side and end walls are made of a single piece of sheet-metal bent into shape; third, a box or case having a sliding cover which may be applied and removed from either end of the case; and, fourth, a box or case having improved guiding and securing means for the sliding cover.

The invention consists of the features of construction, combination and arrangement of parts hereinafter fully described and claimed, reference being had to the accompanying drawing, in which:

Figure 1 is a perspective view of a closed shipping box or crate embodying my invention. Fig. 2 is a horizontal section through the same. Fig. 3 is a vertical cross-section. Fig. 4 is a vertical longitudinal section.

The box or case is of rectangular or oblong rectangular form and comprises a bottom 1, preferably formed of wood, and a body 2, the latter formed of a single piece of sheet-metal. As shown, the metal, which is primarily in the shape of a continuous strip, is bent to produce the side walls 3 and end walls 4. One of the ends of the metallic strip is bent to form a flange 5 and the other end bent to form a retaining hook 6 which interlocks with said flange, thus forming a seam uniting the free portions of the strip at one of the corner portions of the body. The bottom 1 is secured to the lower edges of the side and end walls by nails or analogous fastenings 7, whereby it is permanently secured in position. In the use of the device as a shipping case or crate for eggs and other articles requiring the subdivision of the box into compartments, a transverse partition 8 is employed which is secured to the side walls 3 by nails or similar fastenings 9, and in conjunction with this partition the ordinary card-board fillers may be used.

The top of the box or case is designed to be closed by a sliding cover 10. This cover

is provided with inturned side flanges 11 to engage outturned guide flanges 12 on the upper edges of the walls 3, such flanges 12 being formed by outwardly and inwardly extending or folded portions of the metal to give increased strength. The end walls 4 of the box are provided at their upper edges with similar flanges 13, which are alike in construction, and each of which is formed with an opening 14. The cover 10 is formed at one end with a hook shaped flange 15 and at its other end with a flat flange 16 having an opening 17. The cover is adapted to be applied and removed from either end of the case for greater convenience in closing and opening the same, and the hooked flange 15 is accordingly adapted to interlock with either of the flanges 13, while the flange 16 is adapted to rest upon the upper surface of either of said flanges 13 with its opening 17 in registry with the opening 14 therein. It will thus be seen that when the cover is slid on from one end, its hooked flange 15 will engage the flange 13 of the body at that end, while its flange 16 will rest upon the upper surface of the flange 13 at the opposite end of the body, and that when the cover is slipped on from the other end of the body the flanges 15 and 16 will engage the flanges 13 in reverse order from that above described. In order to adapt the cover to be applied and removed in this manner, interchangeably from either end of the case, the ends of the flanges 12 and 13 are obliquely cut away at the corners of the body, while the corner portions 18 of the cover are also obliquely cut away to separate the ends of the side and end flanges 11, 15 and 16 and thus form clearance spaces to facilitate and admit of the engagement of such flanges with the flanges on the body. Any suitable locking means may be employed to secure the cover in position. In the present instance, I have shown a tie cord or wire 19 threaded through the opening 17 in the flange 16 and the opening 14 in the underlying flange 13 of the body, the ends of the cord extending outward and being connected by a suitable seal 20. It will be understood, of course, that the usual shipping tag may be attached by this cord to the case and a seal of any suitable form and construction employed, and which, if desired, may form with the tie a fastening means which can only be disconnected by opening or destroying the seal, so that if the case is tampered with in transit

visual evidence of that fact will be given. Wooden strips or cleats 21 are secured upon the outer sides of the end walls 4 to form transverse hand grips and are secured in position by nails or equivalent fastenings 22 which are clenched upon the inner sides of said walls to firmly fasten the cleats thereto.

It will be seen from the foregoing description that the invention provides a shipping case or crate which is strong and durable and may be inexpensively manufactured, since the body of the crate is composed of a single piece of sheet metal bent into shape; that the mode of applying and removing the cover affords increased convenience in the operation of opening and closing the container; and that a simple and effective means for securing the cover in position is employed.

Having thus fully described the invention, what is claimed as new is:—

1. A box or case comprising a body having outturned side flanges and outturned end flanges obliquely cut away at their ends, each of said end flanges being formed with an opening, a cover provided with inturned side flanges to slidably engage the side flanges of the body and with end flanges to coöperate with the end flanges of the body, and cut away at its corners to separate the ends of said flanges and form clearance spaces, one of the said end flanges of the cover being in the form of a hook to engage one of the end flanges of the body and the other end flange of the cover being flat to rest upon the other end flange of the body and provided with an opening to register with the opening in either end flange of the body, said cover being adapted to be slid onto the body from either end of the latter so that the hooked end flanges of the cover may engage either end flange of the body, while the flat flange of the cover rests upon the other end flange of the body, and a fastening device adapted to be

passed through the opening in the flat flange of the cover and the opening in the end flange of the body engaged thereby to secure the cover in closed position.

2. A box or case comprising a bottom, a body formed of a single piece of sheet-metal bent to form side and end walls, the ends of the piece of sheet-metal being formed with interlocking flanges at the corner junction of one of the side with one of the end walls, said body having at its upper edge outturned side flanges and outturned end flanges obliquely cut away at their ends, each of the end flanges being formed with an opening, a cover provided with inturned side flanges to slidably engage the side flanges of the body and with end flanges to coöperate with the end flanges of the body and cut away at its corners to separate the ends of said flanges and form clearance spaces, one of the said end flanges of the cover being in the form of a hook to engage one of the end flanges of the body and the other end flange of the cover being flat to rest upon the other end flange of the body and provided with an opening to register with the opening in either end flange of the body, said cover being adapted to be slid onto the body from either end of the latter so that the hooked end flanges of the cover may engage either end flange of the cover, while the flat flange of the cover rests upon the other end flange of the body, and a fastening device adapted to be passed through the opening in the flat flange of the cover and the opening in the end flange of the body engaged thereby to secure the cover in closed position.

In testimony whereof I affix my signature in presence of two witnesses.

EGBERT N. BAGLEY.
